UNITED STATES PATENT OFFICE.

JEAN FRANCIS WEBB, JR., OF NEW YORK, N. Y.

ACKNOWLEDGMENT VALVE.

Original application filed February 26, 1925, Serial No. 11,868. Divided and this application filed September 21, 1926. Serial No. 136,857.

My invention, which relates particularly to train stopping apparatus, has for its object to provide a new and improved construction of acknowledgment valve, by means of which 5 the engineer may convert the automatic stop action into a speed control action, and this valve is particularly designed and adapted to function in the train stopping system which constitutes the subject matter of my 10 application filed February 26, 1925, Serial No. 11,868, patented Oct. 12, 1926, No. 1,602, 513, of which application the present one is a division.

More particularly the present invention 15 seeks to provide a simple, rugged construction of valve mechanism in which the use of packing rings and washers is avoided and in which the parts are readily accessible for quick repair or replacement when necessary; 20 to provide a valve structure that is compact in its arrangement of parts and will be self-supporting when connected with the group of pipes with which it cooperates.

In the drawing:

25 Figure 1 is a diagrammatic view of the train stopping system in which my valve is intended to be used.

Figure 2 is a front elevation of the valve.

Figure 3 is a side elevation thereof.

30 Figure 4 is a bottom plan view of the same.

Figure 5 is a vertical section on the line 5—5 of Figure 4.

Referring now to the accompanying drawing in which like numerals of reference indicate like parts in all the figures, 1 represents the engineer valve which is connected to the train line section 2 that in turn connects with the train line 4 through the cut-out cock 3 and double heading cock 5 in the 40 usual manner.

6 designates the automatic train control valve, the construction of which may be that disclosed in my Patent No. 1,487,991, issued March 25, 1924. 7 designates a pipe connecting the cut-out cock with the inlet port 12 of the automatic train control valve 6, while 8 designates a pipe from the cut-out cock to the port 9 of the automatic train control valve 6. The port 9 of the valve 6 is 45 the one that connects with the main chamber of the valve. The outlet port 13 of the train control valve 6 is connected by a pipe 11 to the selective valve 14. 17 is a pipe which connects with the outlet port of the

selective valve 14 and delivers to atmosphere 55 through the indication whistle 18.

The acknowledgment valve mechanism which constitutes the subject matter of the present invention is connected by a pipe 20 to the pipe 7 and is connected by a pipe 21 60 to the selective valve mechanism 14. The acknowledgment valve is also connected by a pipe 23 in which is a check valve 24 to the valve mechanism of the centrifugal speed control governor device 22. 65

From the centrifugal speed control governor device a pipe 25 leads to atmosphere through the speed control whistle 26. 30 designates a pipe from the centrifugal speed control mechanism to the selective valve 14. 70 A blanking valve 27 is employed and a maximum speed control mechanism 28 is associated with the centrifugal governor and connected by a pipe 29 with the blanking valve to control its operation. 75

32 indicates the plunger mechanism and 33 represents the main cam which is operated by the plunger mechanism and in turn operates the automatic train control valve mechanism 6. 80

40 designates the selective valve cam which has a lip to be engaged by the plunger on its up-stroke to turn the cam to bring its lug 42 into the normal position shown diagrammatically in Figure 1, thereby causing 85 movement of the valve-piston of the selective valve mechanism 14 inwardly.

The acknowledgment valve 19 has a handle 60 fulcrumed on a pin 61 and held in the neutral or central position by a spring latch 62. The main chamber 63 of the housing of the acknowledgment valve 19 communicates with branch chambers 64 and 65 through valved passages. The latch 62 has a forked head 62^x in which a cross pin 62^y lies. A 90 spring 60^x presses against a washer 60^y and is held in the hollow handle 60 by the screw cap 60^x to press the latch 62 into constant contact with the notched lug 61^x.

66 designates the inlet to chamber 63 from the train line connection pipe 20 while 67 indicates the valve controlling the passage between chambers 63 and 64, the latter chamber being the branch to which pipe 21 connects. 68 designates the valve between 105 chambers 63 and 65, the latter being the chamber with which the pipe 23 connects. The valves 67 and 68 have stems 69 and 70

respectively which engage the heels 71 of the handle 60 and are operated by movement of the handle in one direction or the other.

5 As the construction of all of the foregoing described parts which are not shown in Figures 2 to 5 inclusive per se constitute no part of the present invention, further description and disclosure thereof in this application is thought to be unnecessary as the construction and operation thereof can be well understood by reference to my original application or the patent issued thereon and referred to aforesaid. Suffice it to say that 10 in using my present invention if the engineman is alive and alert and desires to convert an automatic stop action into a speed controlled action, he moves his acknowledgment valve 19 so as to introduce air (which may be main reservoir air) behind the right hand ring 59 of the piston 57 of the selective valve, and thus push forward (to the left) the piston of the selective valve. This movement cuts off the port to the pipe 17 and indication 15 whistle and connects the chamber between the two selective valve piston rings 59 with the port leading to the speed control mechanism, where the escaping train line air enters the chamber between the two piston rings 117 and 118 of the speed control mechanism.

If the engineman has properly obeyed the caution signal and reduced his speed to, or below, the predetermined minimum, before 20 passing the stop ramp, the chamber between the two piston rings 117 and 118 of the speed control has no port to the atmosphere, and consequently no braking action takes place.

25 If the engineman, however, has passed over the stop ramp above the predetermined minimum speed, the air chamber between the two piston rings of the speed control is connected with the atmosphere through the port leading to the speed control whistle. The escaping train line air thereupon reduces the pressure in the train line until the triple valves effect a brake action, which in turn reduces the speed of the train. When 30 the speed has been reduced to the predetermined minimum, the spring tension of the speed control overcoming the action of the governor balls pushes backward (to the right), the speed control piston cutting off the port to the atmosphere through the speed control whistle. The stopping of this whistle informs the engineman that his speed has been reduced to the predetermined minimum, but his brakes are still set; and, if he wishes to 35 avoid an automatic stop, he must move his acknowledgment valve so that main reser-

voir air can be introduced into the train line by means of the pipe 23 leading through the speed control and the selective valve. Main reservoir air, so introduced, effects a releasing of the brakes with normal rapidity, and the engineman can then proceed at, or below, the predetermined minimum.

40 From the foregoing description, taken in connection with the accompanying drawing, it is thought the complete construction, operation and advantages of my invention will be clear to those skilled in the art.

What I claim is:

45 1. An acknowledgment valve comprising a casing having an inlet chamber and two outlet chambers, said casing having valve-seat passages between said inlet chamber and the respective outlet chambers, said casing having bores through the same into the inlet chamber in alignment with the valve-seat passages, screw plugs located in said bores, valves in said passages for engaging said seats, springs between said valves and the respective screw plugs normally to retain the valves seated, stems for said valves, said casing having bores to the outlet chambers through which said stems project, a lever rockably mounted on said casing and having heels to engage said stems whereby when said lever is rocked in one position one valve will be opened and when rocked in another position the other valve will be opened and vice versa.

50 2. An acknowledgment valve comprising a casing having an inlet chamber and two outlet chambers, said casing having valve-seat passages between said inlet chamber and the respective outlet chambers, said casing having bores through the same into the inlet chamber in alignment with the valve-seat passages, screw plugs located in said bores, valves in said passages for engaging said seats, springs between said valves and the respective screw plugs normally to retain the valves seated, stems for said valves, said casing having bores to the outlet chambers through which said stems project, a lever rockably mounted on said casing and having heels to engage said stems whereby when said lever is rocked in one position one valve will be opened and when rocked in another position the other valve will be opened and vice versa, said casing having supporting ears to which said lever is fulcrumed and said lever having an off-set portion projected over one of said ears, a spring latch carried in said off-set portion to engage a notch in the ear over which the off-set portion projects, substantially as shown and described.
